SEPARATOR

Frank Clay Dugan, Refugio, Tex.

Application May 8, 1936, Serial No. 78,707

1 Claim. (Cl. 183—77)

This invention appertains to new and useful improvements in liquid and gas separators and more particularly to an apparatus for separating gasolene and other liquids from natural gas.

5 The principal object of the present invention is to provide a simple and inexpensive machine through which natural gas can be passed and treated in such a manner as to remove to an efficient and practical extent gasolene and other 10 liquid constituents of the gas.

Another important object of the invention is to provide a machine for separating gasolene and other liquids from natural gas which because of its simple construction is not susceptible 15 to the development of frequent defects.

Other important objects and advantages of the invention will become apparent to the reader of the following specification.

In the drawings:—

20 Figure 1 represents a side elevational view of the machine with a portion of the stator broken away.

Figure 2 represents a longitudinal sectional view through the machine.

25 Figure 3 is a transverse sectional view taken substantially on the line 3—3 of Figure 2.

Figure 4 is a transverse sectional view taken substantially on the line 4—4 of Figure 2.

30 Figure 5 is a fragmentary perspective view of a portion of the coupling of the rotor.

Figure 6 is an enlarged sectional view on line 6—6 of Figure 4.

35 Figure 7 is a diagrammatic view disclosing the manner in which the gas passes between the blades of the rotor.

Referring to the drawings wherein like numerals designate corresponding parts, it can be seen that numeral 5 generally refers to the stator, while numeral 6 generally refers to the 40 rotor. The stator consists of the cylindrical shell 7 and the end walls 8—8 secured thereto by a bolt or rivet 9.

45 Numeral 10 denotes the drive shaft for the rotor 6. A shell construction 11 projects axially from each of the end walls 8, encompassing the adjacent portions of the shaft 10. Each of these shell constructions 11 end in a packing gland 12 through which the shaft 10 extends.

50 Numeral 13 is the natural gas conduit communicating with one of the shells 11 while numeral 14 is the take-off conduit for the gas. Furthermore, numeral 15 represents the outlet from the stator 5 of gasolene or other liquids 55 removed from the natural gas.

The rotor 6 consists of a cylindrical shell 16 having a multiplicity of openings 17 therein. The shell 16 is provided with the end walls 18—18 suitably bolted or riveted thereto.

Blade assemblies 19 and funnel assemblies 20 are mounted within the rotor 6. The blade assemblies 19 serve to draw the gas and other substances through the machine, while the funnel assemblies 20 catch the liquids and other heavier substances and by centrifugal force throw them 10 outwardly, through the openings of the shell 16, where they run down the inside of the cylindrical wall 7 of the stator and finally drain through the outlet 15, while the remaining gas passes out through the conduit 14. 15

The blade assemblies 19 are on hubs 21, while the funnel assemblies 20 are on axial disks 22. Split collars 23 suitably bolted together as at 24 are provided on the drive shaft, one at each end of the rotor 6 and set screws 25 serve to 20 retain these collars in definite position on the shaft. These split collars 23 are provided with openings 26 therein through which the end of the tie rods 27 extend. These tie rods extend through all of the hubs 21 and axial disks 22, 25 so that all of these members are interlocked together and definitely fixed on the shaft 10.

The periphery of each of these assemblies 19—20 is provided with an annulus 28—29 respectively. 30

As clearly shown in Figure 3, rods 30 extend from the hubs 21 to attach at their outer ends to the annular members 28 and suitably secured to each of these rods 30 are the blades 31 disposed obliquely with respect to the longitudinal 35 axis of the rotor and these blades gradually reduce the side toward the axis of the rotor as is clearly shown in Figure 3.

The funnel assembly 20 consists of plate members 32 radiating from the axial disk 22. These 40 plates 32 gradually increase in width to the point where they attach to the annulus 29 and are secured to the shell 16. One longitudinal edge of each of these plates 32 is rolled to form an open tube 33 having its edge 34 in spaced 45 relation to the plate proper 32. The heavy particles of the natural gas are caught in these tubes under force exerted by the blades 31 and by centrifugal force are thrown outwardly through the openings in the shell 16 to finally 50 drain through the outlet 15 in the stator 5.

It will be observed that the shell 16 is provided with perforations 17 and that the assemblies of blades 31 and tubes 33 are alternately positioned longitudinally. The blades 31 serve to rotate 55

the gas at the desired speed and to force the gas against the tube assemblies. As suggested in Figure 4, these tubes while opened longitudinally are also curved longitudinally and act as accumulators in receiving the heavy particles or liquids from the gas and to deliver this heavy part of the gas to the periphery of the rotor and through the perforated shell 16 to the space between the shell 16 and the casing 7 from which space this heavy portion of the gas can be taken off by way of the outlet 15. The blades 31 assist the tubes forcing more of the gas into the tubes than would ordinarily be taken in by the tubing effect of the tubes, with the result that the actual centrifugal deliverance of the heavy portion of the gas is forced by the action of the blades 31.

While the foregoing specification sets forth the invention in specific terms, it is to be understood that numerous changes in the shape, size, and materials may be resorted to without depart-

ing from the spirit and scope of the invention as claimed hereinafter.

Having described the invention, what is claimed is:—

A separator of the character described comprising a stator, a rotor mounted in the stator, an inlet at one end of the stator, an outlet at the opposite end of the stator, said rotor being hollow and provided with blades radially disposed from the axle and on oblique planes with respect thereto, said rotor being provided with a plurality of radially disposed tubular structures open longitudinally for catching heavy particles of gas forced toward the same by the fans and discharging the same centrifugally from their outer ends toward the stator, the periphery of the rotor being in spaced relation to the stator, said rotor including a surrounding shell perforated to permit the escape of gas into the space between the rotor and the stator. 20

FRANK CLAY DUGAN.
